UNITED STATES PATENT OFFICE.

JAMES MILTON WAUGH, OF CHICAGO, ILLINOIS.

BUMPING BLOCK OR POST FOR RAILWAYS.

1,104,332.

Specification of Letters Patent. Patented July 21, 1914.

Application filed September 6, 1912. Serial No. 718,793.

To all whom it may concern:

Be it known that I, JAMES MILTON WAUGH, a citizen of the United States, and a resident of the city of Chicago, in the county of Cook and State of Illinois, have invented certain new and useful Improvements in Bumping Blocks or Posts for Railways; and I do hereby declare that the following is a full, clear, and exact description 10 of the same, reference being had to the accompanying drawings, and to the numbers of reference marked thereon, which form a part of this specification.

It has become common railway practice 15 for all track or switch ends to be equipped with bumping posts or blocks to prevent the rolling stock from running over the track ends. Such bumping posts have assumed many different forms, and in some instances 20 a spring buffering gear is positioned thereon to be struck by the drawhead of the car to assist the buffering gear of the car in absorbing the shock of impact. In some instances, the rail ends of the track are bent upwardly and 25 bolted together at the rear of the bumping posts to tie the same to the track rails. As heretofore constructed, said bumping posts, even when equipped with a buffering gear, frequently cause very serious damage to the 30 cars, sometimes wrecking the end of the car because of the lack of adequate means for absorbing the stresses occasioned by the impact of the car thereagainst. Such stresses are frequently very great and the demolition 35 of at least the draft gear on the car is almost certain to occur where such bumping posts are used. As heretofore constructed, if any buffering gear at all is used on the post, such gears have utilized coiled springs to a 40 greater or less extent and the recoil or rebound of such springs after each impact is a serious occasion for damage. Of course, the failure of the draft and buffering gear on the car is almost invariably accompanied by 45 more or less injury to the car end.

The object of this invention is to provide a bumping post or block so constructed as to surely arrest the movement of the car before derailment, and also equipped with a 50 buffering gear whereby the stress of impact is received in alignment with the center sills of the car, and absorbed frictionally, eliminating violent recoil.

It is also an object of the invention to

afford a construction in which a plurality of 55 buffering gears are arranged side by side to receive the shock of impact, one of the same being arranged centrally for engagement by the drawhead, and others disposed laterally to engage the end sill of the car in alignment 60 with the center sills, said laterally disposed buffering gears being so constructed as to absorb the stress of impact before the limit of capacity of the buffering gear of the car is reached, thereby eliminating the danger of 65 injury to the draft gear.

It is also an object of the invention to mount a plurality of buffering gears side by side upon an exceedingly rigid bumping post to distribute the shock of impact directly 70 to the center sills of the car.

The invention (in a preferred form) is illustrated in the drawings, and hereinafter more fully described.

In the drawings: Figure 1 is a side elevation of a device embodying my invention, and showing the car diagrammatically. Fig. 2 is a top plan view thereof. Fig. 3 is an enlarged top plan view with the concrete foundation and body shown in dotted 75 lines. Fig. 4 is a side elevation thereof. Fig. 5 is a front elevation thereof. Fig. 6 is an enlarged, horizontal section taken through the lateral buffering gears, the central buffering gear being shown in dotted lines. 80

As shown in the drawings: 1, indicates the concrete base and body of the post. Mounted thereon are three buffering gear casings of cast metal, comprising the laterally disposed draft casings 2, and the centrally 85 disposed draft casing 3, which connects and lies below the same. Said three draft casings are integral, and are open at their front or buffering ends and each comprises a horizontally disposed draft gear casing open at the front end, and in which are secured groups of flat spring steel plates 4, any desired number of which may be used in forming a group, and which fill said pockets for substantially the full extent thereof. At 100 the inner end of each of said bevel gear pockets, is a rounded or convex block 5, against which the inner group 4, bears, and alternating from the inner end of each of said casings or pockets to the outer end 105 thereof, and disposed between adjacent groups, are double concave and double convex spacing members 6 and 7, against which

said groups of springs bear alternately at their middles and at their ends. Inserted in the otherwise open end of each of said casings is a bevel head 8, which is rounded or convex on its inner face to correspond with the convexity of the block 5, and integrally connected therewith is an outwardly extending strong broad web 9, of metal, which projects beyond the ends of said casing, as shown in Fig. 6. Said groups of springs are secured in said casing under considerable pressure, and to this end the bevel heads 8, are forced inwardly to slightly compress the spring groups in the respective pockets, and a bar plate 10, is bolted over the web or stem 9, of the buffer blocks, and is bolted to the end of the casing, thereby limiting the outward travel of the buffer heads on recoil. Adjustably secured on the webs or stems 9, of the buffering blocks, is a buffering beam 11. This is shown as recessed near its ends and on its rear side to receive the stems 9, thereon, as shown in Fig. 6, to impart shock of impact to the buffering spring, and is concaved centrally and horizontally on its front side to receive the rounded platform ends of a passenger car therein, if desired. From a point nearly coincident with the inner edge of the webs or stems 9, said buffering bar or beam 11, is flattened to the ends to receive the impact of the end sills of the car, said flattened portions being disposed to be engaged by the end sills at points opposite the ends of the center sills of the car.

The central buffering gear casing 3, is preferably cast or constructed integrally with the gear casings 2, before described, and lies sufficiently below the same to be in alignment with the draft and buffering gear of the car, as shown in Fig. 1. Said casing is relatively short and is provided at its inner end with the convex filler block 12, against which the first group of springs shown in dotted lines in Fig. 2, abuts at its middle, and arranged alternately between succeeding groups are double concave and double convex filling or spacing blocks 13 and 14 respectively, which separate said groups so that the groups bear successively thereon at their ends and at points intermediate their ends. The buffering block 15, is convex on its inner side, and bears against the outer group of springs, and is provided with an integral head or buffering stem 16, which projects through an aperture in the casing plate 17, which is bolted on the otherwise open end of said casing and is so disposed as to hold the buffering head 15, inwardly sufficiently to slightly tension the groups of springs at all times. Said buffering gear casings are mounted upon said foundation post or block 1, of concrete, which is molded thereto, and a T rail stirrup is constructed by suitably bending a rail (for example, a sixty foot railway rail) so that when the ends thereof are

spliced to the ends of the track rails, as shown in Fig. 1, a horizontal portion 18, at said ends continues said track rails onto said concrete foundation to which the same is secured by the bolts 19, and clamping bar 20, and thence inclines upwardly as indicated at 21, and extends around said casings 2, fitting closely thereto, as shown in Figs. 1 to 4 inclusive, and rigidly holding said casings in place. As shown, bolts 23, engage through each end of the clamping bar 24, which extends transversely said casings approximately over the front end of the intermediate casing 3, and are bedded in said concrete, and if desired, provided at the lower ends with nuts 25, accessible through a recess in said concrete foundation, where the same may be set up. Each of said casings is provided integrally therewith on the rear end thereof, with downwardly directed brackets 26 and 27, which are directed downwardly at an angle of approximately forty five degrees, and are adapted to receive therebetween I beam brace bars 28 and 29, which are rigidly bolted or riveted therein, and which at their lower ends engage in complementary brackets 30 and 31, constructed integrally on a relatively broad foot plate 32, engaged on the foundation, and which is rigidly tied to the front of the foundation or post by means of tie rods or bolts 33, which extend through angle bars 34, which engage against the front of the foundation or post and over the inclined rails 21, and extend through apertured lugs 35, extending outwardly from each end of said foot or base plate 32.

When assembled, concrete is molded in any desired thickness upon the back of the post, covering the brace bars 28 and 29, and filling the spaces therebetween, and bonding upon the metal structure described, affords a reinforced concrete construction of enormous strength.

The operation is as follows: In passenger cars, the drawhead extends but very slightly beyond the end sill or platform, and in consequence in many instances the drawhead may not engage the central buffer head 16, at all. Instead, the buffer plate first engages against the buffer rail or beam 11, the buffer plates are pressed back flat against the end sill, and the entire impact is absorbed by the laterally disposed buffering gears which engage said end sills point blank in alignment with the center sills of the car. The buffer beam is driven inwardly, thereby compressing the flat friction springs in the laterally disposed buffering casings, the resistance of said springs and absorbing power due to the frictional bearing of the successive plates one upon another, rapidly augmenting with the movement, until the stress is absorbed, and damage obviated.

With other than passenger cars, the drawhead projects beyond the end sill and en-

gages the buffing stem or head 16, as shown in Figs. 1 and 2, and the buffing gear upon the car and the corresponding buffing gear upon the bumping post, have begun to absorb the stress of impact before the end sill 5 engages the buffing beam 11. The buffing beam 11, having been engaged by the end sill, all the buffing mechanism, including that on said end of the car, are brought into 10 action to absorb the stress of impact. Inasmuch, however, as the central buffing gear on the bumping post and the buffing gear on the car afford somewhat longer travel in compression than the lateral bumping gears 15 on the post, it follows that the buffing gear on the car can never be driven solid to affect the shearing of the supporting bolts or rivets. Instead, the maximum stress is taken and absorbed by the lateral buffing gears on 20 the post, which, as before described, brings all the stresses into alinement with the center sills of the car and absorbs the same.

In a construction such as described, the individual spring plates of the various 25 groups lying flat face to face, afford large frictional contact surfaces, and in consequence the absorption of the stresses through friction increases enormously with the compression, and owing to the positive 30 frictional engagement face to face of said plates, and the large number of groups, recoil is almost wholly absorbed and instead of the violent and destructive rebound occasioned when buffing gears of other constructions are used on the bumping post, the 35 gears gently move back to normal and without possibility of injuring the rolling stock.

Of course, details of construction may be varied dependent upon the service required, 40 and the number of groups of springs, and the number of springs in the groups in the respective buffing gears will vary accordingly. I have shown but a preferred form of my invention, and I do not purpose limiting the 45 patent granted therefor otherwise than necessitated by the prior art.

I claim as my invention:

1. A bumping post and resilient buffing 50 gears secured thereon and positioned to engage the extremity of the car in alinement with the center sills of the car.

2. A bumping post embracing a base or foundation and a plurality of spring bumping or buffing gears rigidly secured thereon 55 side by side in position to engage the end sill of the car in alinement with the center sills thereof and to engage the drawhead of the car approximately simultaneously therewith.

60 3. In a device of the class described a plurality of rigidly connected parallel casings arranged horizontally substantially at the level of the end sill of a car and in alinement with the draw head thereof respectively, resilient friction members ar-

ranged in groups in each casing, and buffing heads engaged in the respective casings and bearing against the outermost of said groups and adapted to be respectively engaged by the end sill of the car and in alinement with 70 the center sills and by the drawhead of the car, thereby utilizing said bumping gears and the buffing gear simultaneously in absorbing impacts.

4. A bumping post of reinforced concrete, 75 a central buffing gear rigidly secured thereon in position to be engaged by the drawhead of the car, laterally disposed bumping gears rigidly secured on said bumping post above the same, and a transverse beam 80 carried on the outer ends thereof, and adapted to receive the impact of the end sill of the car substantially in alinement with the center sills whereby stresses of impact are absorbed in said bumping gears in the under 85 frame of the car and in the buffing gear of the car, all acting simultaneously to receive the same.

5. In a bumping post a rigid post, and 90 resilient bumping gears of high capacity rigidly secured thereon in position to impact the end sill of a car in alinement with the center sills thereof.

6. In a device of the class described a rigid bumping post, a resilient bumping gear 95 rigidly secured thereon on each side the center in alinement with the center sills of a car to be stopped thereby, and embracing friction spring mechanism of high absorbing capacity, an intermediate bumping gear 100 of less stress absorbing capacity secured on said post in position to be engaged by the drawhead of the car approximately simultaneously with the engagement thereof by the main bumping gears, and downwardly 105 and rearwardly inclined brace bars rigidly secured to each of said bumping gears and rigidly anchored in the foundation and acting to deliver the stress of the impact to the ground.

7. In a device of the class described a bumping post, a plurality of resilient bumping gears secured thereon side by side in position to be impacted by the end sills of the car in alinement with the center sills thereof 110 and by the drawhead of the car respectively, brace bars extending obliquely downwardly and rearwardly from the respective bumping gear rigidly anchored in the foundation, a track rail bent centrally to afford 115 a stirrup to engage around the rear ends of said bumping gears at its middle part, and to incline thence downwardly and forwardly to the track, and with the ends thereof connected with the track rails, and tie 120 bars engaging around the front of said posts and over said rails, and rigidly connected with the lower ends of the brace bars to tie the same together.

8. In a device of the class described a bump- 125

ing gear casing embracing relatively long cast metal casings, an intermediate and relatively short casing integrally connected therewith and lying below the same, a succession of 5 groups of spring plates arranged in all of said casings to bear successively at their middles and at their ends upon the casings and each other, buffering stems or heads engaged in the open ends thereof to tension 10 said spring groups and in alignment respectively with the center sills of the car to be stopped and with the drawhead thereof, and a beam connecting the buffering stems in the upper and laterally disposed casings and 15 adapted to afford a broad bearing for engagement by the end sill of the car.

9. In a device of the class described spring friction bumping gears adapted respectively to engage the car end in alignment with the center sills and to engage the drawhead, and acting to absorb the stress of impact and also recoil.

10. In a device of the class described three buffering gears rigidly supported to act in alignment with the center sills of the car and the drawhead thereof, those acting in alignment with the center sills having high capacity, those acting in alignment with the drawhead having together with the normal buffering gear of the car, substantially the same capacity for absorbing stresses as the laterally disposed buffering gears.

11. In a device of the class described embracing a rigid base, buffering gears secured thereon one above the other, one in alignment with the draft gear of a car, the other in alignment with the platform and acting simultaneously by engagement thereof with the drawhead and the platform end 40 to absorb the buffering stresses of the car to be stopped.

12. A non-recoiling buffering block comprising a plurality of draft gears, one of said gears adapted to be contacted by a drawhead of a car, and the other of said gears connected to one another and adapted to be contacted by the end sill of a car independently of said first mentioned gear.

13. A buffering block adapted to receive 50 the shock of the car without recoil, a track rail forming a part of the track bent around and forming a part of said block, rearwardly directed members connected to said track rail to resist the impact of a car, tie 55 rods connecting said members and said track rail, buffering gears mounted on said block adapted to be contacted by a car, and concrete molded in and around said members to maintain the same in immovable relation.

14. A shock absorber bumper friction plates block adapted to be contacted and actuated by the end sills of a car.

15. In a buffering block of the class described shock absorbing means composed of

spring friction plates one set adapted to receive the impact from a drawbar, and the others to receive the impact from the end sills independently of said first set.

16. In a device of the class described a 70 plurality of friction plate draft gears, connections between certain thereof to receive the shock from the car end sills, and an independently operable gear arranged below said connected gears to receive the impact of 75 the drawhead of the cars.

17. In a device of the class described a plurality of independently operable draft gears, one adapted to be operated by the drawbar and the other by the end sill of a 80 car.

18. In a device of the class described a plurality of draft gears, one actuatable by the drawbar of a car, and an equalizing bar connecting the others adapted to be actuated 85 by the end sill of a car.

19. In a buffering block, shock absorbing means actuatable by the drawbar of a car, shock absorbing means actuatable by the end sill of a car, each of said means operable irrespective of the operation of the other.

20. In a device of the class described a plurality of independently actuatable draft gears arranged one above the other adapted to be actuated by the drawbar and end sills 95 of a car respectively.

21. In a device of the class described a plurality of buffering gears acting independently of one another, a support therefor comprising a foundation of concrete, a retaining stirrup placed therearound and formed from one of the track rails, rearwardly directed members adapted to resist impact, and tie rods connecting said rearwardly directed members and said track rail 100 stirrup and said buffering gears.

22. In a device of the class described a foundation of concrete, the extremities of railroad rails bent therearound to secure the foundation to the track, rearwardly directed 110 inclined members adapted to anchor the same against impact, and a plurality of buffering gears adapted to contact different portions of the end of a car and act independently of one another.

23. A buffering block comprising a plurality of draft gears mounted thereon, and a reinforced concrete foundation therefor, the reinforcing members of which are integral with the track rails of a railroad track.

24. In a device of the class described a foundation of concrete, the end rails of a railroad track embedded therein, rearwardly downwardly directed steel reinforcing members, tie rods connecting said railroad rails and said reinforcing members, and a plurality of buffering gears mounted thereon.

25. In a device of the class described shock absorbing means adapted to contact 130

the end sill of a car, independent shock absorbing means adapted to contact a draw-bar of a car, and means adapted to connect said first mentioned means permitting differential thereof when the impact is not applied centrally.

In testimony whereof I have hereunto

subscribed my name in the presence of two subscribing witnesses.
